AUTOMATIC EMERGENCY BRAKE SETTING DEVICE

Frank P. Holmes, Memphis, Tenn.

Application September 11, 1936, Serial No. 100,303

2 Claims. (Cl. 246—170)

This invention relates to an automatic emergency braking device for stopping trains, and particularly to means for stopping a train in the event of derailment of any of the units of the 5 train.

The object of the invention is to incorporate this device on all railway equipment in road service in connection with the air brakes now in service, with the view and intention of averting 10 railroad wrecks, whereby the moment the car on which it is attached leaves the rails and hits the ties, the device will become functionally operative to cause the air brakes to be set instantly as in an emergency application thereof, throughout 15 the entire train which cannot move until such adjustments are made to release the air brakes on the entire train.

Another object of this invention relates to the applicability of the same to freight or passenger 20 cars without any material alteration in the construction thereof, and fulfilling the intended purpose in an effective manner.

The invention consists in the novel construction and combination of parts hereinafter particularly set forth and pointed out in the claims; it being understood that while the drawings show the preferred embodiment of this invention, I do not wish to be limited to the exact construction, but desire to make such changes in the form, 25 size, proportion and minor details of construction as will come within the scope of the appended claims.

In the drawings:—

Figure 1 is an end view of so much of a railway 35 truck as seems necessary to disclose in order to show the application of the invention thereto.

Figure 2 is a similar partial view of the truck shown in a derailed position with the invention shown in an operative position.

Figure 3 is a detail sectional view showing the 40 operating lever connection to the brake system taken on line 3—3, Figure 1.

Figure 4 is a detail sectional view showing the 45 operative lever mounting taken on line 4—4, Figure 1.

Figure 5 is a detail sectional view showing the 50 operating lever guide, taken on line 5—5, Figure 1.

Figure 6 is a detail sectional view through a 55 part of the brake setting device taken on line 6—6, Figure 1.

Referring to the drawings, the car truck indicated, which may be of any standard or desired form, is provided with the wheels 10 mounted on 55 the axle 11 which is supported within the journal

boxes 12 mounted in the side-frames 13. Suitably supported on springs (not shown) is a bolster 14 which supports through the medium of the center bearing 15 the body truss on girder 16. Bridging the side frames 13 is a sand board 17. 5 The wheels 10 rest on the rails 19 which are supported on the ties 20.

Depending from the center portion of the sand board 17 is a bracket 22 rigidly secured thereto by the rivets 23. Carried by the bracket 22 is a 10 projecting pivot pin 24 on which is pivotally mounted parallel to the sand board 17 the operating lever 25 of the automatic emergency brake device. Preferably washers 26 are arranged on the pin 24 on each side of the lever 25, the whole 15 being retained on the pin by the cotter-pin 27. The operating lever 25 is formed of substantially heavy stock and comprises a wide center portion 28 and two oppositely extending tapering arms 29 and 30. In the normal position of the lever 25 20 the arm 29 is horizontal, the center portion 28 is inclined upwardly and to the right therefrom, the arm 30 projecting substantially horizontal from the upper end thereof. The dimensions of the lever 25 and its supporting bracket 22 are such 25 that the end of the lower arm 29 extends transversely across the rail 19, clearing the side frame by substantially 3" and no closer to the rail than 2 $\frac{3}{4}$ " in accordance with the Master Car Builders' rules. To guide the lever 25 in its movement 30 and to prevent the same from engaging the rail (in its normal position) there is provided a loop 32 formed of strap iron rigidly secured as by the rivet 33 to the sand board 17.

Running longitudinally of the car is the usual 35 train air pipe 35 provided with a cut-out valve 36 connected thereto by a short nipple 37, the connection being such that the same is in a plane forwardly of the bolster 14 by a substantial distance. Threaded into the cut-out valve 36 is a 40 length of cast-iron pipe 38 provided at its free end with a cap 39 and held in place by a bracket 40 positioned close to the cut-out valve and rigidly secured to the frame 16 as by the rivets 41.

The end of the lever arm 30 is connected to the 45 end of the cast iron pipe 38 by a length of chain 45 and a rod 46. One end of the chain 45 is connected to an eye 47 of the rod 46, the other end of the chain being secured to the end of the lever arm 30 by a bolt 48. The upper end of the rod 50 46 is provided with a looped end 49 and is rigidly clamped to the end of the cast-iron pipe 38 through the medium of the bolt 50.

The links of the chain 45, shown six in number, constitute a medium to take out lost motion, 55

and should be made so nearly taut in applying to empty cars that it will not bind and put any undue strain on the cast iron pipe 38. In a loaded car of 90,000 to 110,000 pound capacity 5 there will be a $\frac{3}{4}$ " to 1" slack in the chain sufficient to accommodate the up and down movement of the bolster.

Referring to Figure 2, the operation of the device will be readily apparent. The car truck is 10 shown derailed in which position the end of the lever arm 29 is in contact with the rail. As the height of a standard rail is from 6 to 6 $\frac{1}{2}$ inches from the ties, and the distance the end of the lever arm clears the rail is approximately 3" 15 (in its normal position, Figure 1) the wheel 10 when it jumps the rail 19 will travel downwardly approximately 3" before end of lever arm will engage the top of the rail. Further downward movement of the wheel 10 amounting to 3-3 $\frac{3}{4}$ " 20 (inches) will act to force lever 25 in a clockwise direction about its fulcrum 24 which movement will impart a downward pull on the chain 45 and pull rod 46;—the sudden force exerted by this movement will cause the cast iron pipe 38 to 25 break in the manner shown, allowing the air to escape from the train line 35, and setting the air brakes in the entire train without warning. This action will occur simultaneously with the wheels 10 of the truck engaging the ties thus stopping 30 the entire train with a consequent avoiding of a wreck.

With the application of this device to each of the trucks in a railway or freight car, engine and tender, the derailment of any one truck in the

entire train will act to automatically stop the same.

Having thus set forth and disclosed the nature of this invention, what is claimed is:

1. A safety device for a railway car equipped 5 with air brakes, and having a truck, said brake equipment including the usual train pipe adapted to allow application of said brakes by reduction in pressure in said pipe, said device including a frangible tube connected to said train pipe and 10 rigidly supported by the body of said car, said tube extending laterally from said support and being closed at its outer end; a lever extending transversely of said truck and pivotally secured intermediate its ends to an unsprung part there- 15 of the outer end of said lever extending across a rail of the track on which said truck is carried and spaced thereabove a distance such that the lever will strike the rail in event of derailment or the like, and the inner end extending beneath the 20 closed end of said tube; and a flexible non-exten- 25 sible, substantially vertical member, connecting said tube end and the inner end of said lever, said connection having initial slack sufficient only to allow spring action, side sway and turn- 30 ing movement of said truck and lever, relative to said body and tube.

2. A safety device in accordance with claim 1 having a keeper member supported by an un- 30 sprung part of said truck; and positioned inter- 35 mediate the outer end of said lever and said lever pivot, said keeper member limiting down- 40 ward movement of said outer end.

FRANK P. HOLMES.
